UNITED STATES PATENT OFFICE

EDWARD GODFREY BREWER, OF TEDDINGTON, ENGLAND

MACHINE FOR CLEANING GOLF AND OTHER BALLS

Application filed October 9, 1928, Serial No. 311,332, and in Great Britain August 10, 1928.

This invention relates to an improved machine for cleaning golf and like balls. The machine is suitable for attachment to a small bench or table in the dressing rooms of golf clubs and is so constructed that a predetermined number of balls may be cleaned at one operation of the machine.

According to the invention the machine consists of a cylindrical body open at the top and having a solid bottom plate centrally through which bottom plate passes a vertical tube, which forms a bearing for a spindle carrying a brush. The vertical tube extends upward above the bottom plate thus forming an annular watertight space to receive a washing fluid in which the balls revolve. The machine is firmly attached to a bench by bolts or the like passing through lugs formed on the body of the machine. A circular groove, in which rest the balls to be cleaned, is formed eccentrically in the bottom plate of the body. A circular cage resting on projections formed on the interior surface of the body and having holes through which the balls to be cleaned are placed, is mounted loosely on and is free to rotate round the central vertical tube. The holes formed in the circular cage are of a convenient size to receive the balls to be cleaned, and are elongated and have semi-circular ends and the major axes of these elongated holes are arranged radially to the centre of the machine.

A brush, consisting of a disc to which are attached bristles annularly or circularly arranged, is fixed to the spindle carried in the central vertical tube, in which it is adapted to be rotated by a handle.

A suitable brake may be provided to contact with the periphery of the circular cage.

The mode of operation of the machine is as follows:—

The machine having been charged with a suitable washing fluid such as a mixture of water, soap and sand to a depth of about half an inch, the brush to which the spindle and handle are firmly attached, is lifted out of the machine and as many balls as it is desired to clean, up to the capacity of the machine, are placed in the holes of the cage and

rest in the eccentrically arranged circular groove formed in the bottom plate of the body. The brush is then replaced and rests with its full weight on top of the balls. The handle may then be turned in either direction 55 to rotate the brush, and the balls will then revolve in the eccentrically arranged circular groove, thereby a scouring action being imparted to the surface of the balls radially across the surface of the bristles of the brush 60 in the presence of the washing fluid. The brush will then be worn evenly over its whole surface and not in ridges.

If the brake be operated to retard the rotation of the circular cage, the balls will be 65 brushed harder by the bristles, because the friction between the balls and the bristles is increased by retarding the rate of rotation of the balls.

Means are also provided for preventing 70 damage to the bristles of the brush in the event of rough treatment or carelessness by the operator, in which the spindle carrying the brush is screwthreaded to receive a pair of nuts, the lower of which bears upon the 75 upper end of the central vertical tube, when the handle is forced in a downward direction and thus limiting the downward motion of the spindle and preventing the bristles from being pressed too forcibly in contact with the 80 balls being cleaned.

An example of construction will now be described with reference to the accompanying drawings in which Fig. 1 is a vertical section on the line X—Y of Fig. 2 of ball cleaning 85 machine according to this invention, Fig. 2 is a plan with the brush, spindle and handle removed, Fig. 3 a plan view of the body of the machine with the brush, spindle, handle and cage removed.

Figs. 4, 5 and 6 show in sectional side elevation the position assumed relatively to the brush by a ball, whilst travelling in the eccentric groove. Fig. 7 shows means for preventing damage to the brush in the event of rough 95 treatment or carelessness by the operator.

Referring to the drawings, the machine is constructed with a vertical cylindrical body A open at the top and having a solid bottom plate A¹, centrally through which bottom 100

passes a vertical tube A², which forms the bearing for the spindle B carrying the brush C. The vertical tube A² extends upwards above the bottom plate A¹, thus forming an annular watertight space to receive the washing fluid G in which the balls revolve. The machine is mounted on the table D and is attached thereto with the aid of bolts or the like passing through lugs on the machine. A circular groove A³ which is located in the bottom A¹ of the body A, is eccentrically arranged therein, see particularly Fig. 3.

A circular cage E, resting on projections A⁴ formed on the interior surface of the body A and having holes E¹, is mounted loosely on and is free to rotate around the vertical tube A². The holes E¹, which in the example illustrated are six in number, are arranged in the cage E with their major axes radiating from the centre of the machine and having semi-circular ends.

A hole A⁵ is formed in the wall of the body A, through which a brake A⁷ in a bearing A⁶ projects and contacts with the periphery of the cage E.

The brush consisting of a disc C, to the underside of which is attached an annular ring of bristles C¹, is fixed to the spindle B and has attached to it a handle B¹.

F indicates the balls to be cleaned.

The mode of operation of the example of construction illustrated is as follows:—

The machine having been charged with the fluid G, the brush C which is attached firmly to the spindle B, is lifted out from the cylindrical body A conveniently by the handle B¹ and as many balls as it is desired to clean, up to a total number of six, in the machine illustrated, are inserted in the holes E¹ of the cage E, through which they project. The balls F rest in the eccentrically arranged circular groove A³ formed in the bottom plate A¹ of the body A, and the brush C is then replaced and rests with its full weight on top of the balls F.

The handle B¹ may then be turned in either direction to rotate the brush C and the balls F will then revolve and be rotated in the groove A³, thereby a scouring being imparted to the surface of the balls F radially across the surface of the bristles C¹ in the presence of the washing fluid, which is continuously supplied to the surface of the balls by their rotation.

The brake A⁷ may be pressed inwardly by the hand of the operator during the cleaning operation and contacts with the periphery of the cage E, retarding its rate of rotation and consequently the rate of rotation of the balls F, the friction between the balls F and the bristles C¹ is thus increased and the balls are brushed harder.

In Fig. 7 there is illustrated means for preventing damage to the bristles of the brush in the event of rough treatment or careless

ness by the operator, in which the spindle B is screw-threaded to receive a pair of nuts B³, B⁴, the lower of which bears upon the upper end of the vertical tube A² when the handle B¹ is forced in a downward direction and thus prevents the spindle from moving too far downwardly and the bristles C¹ from being forced downwards and damaged by too hard a contact with the balls F. The vertical position of the nuts B³, B⁴ on the spindle B may be regulated as desired.

What I claim as my invention and desire to secure by Letters Patent is:—

1. A machine for cleaning golf and like balls comprising in combination, a cylindrical casing, a base to such cylindrical casing containing a circular groove eccentrically arranged relatively to the axis of said cylindrical casing, a brush rotatably mounted and adapted to contact with the upper surface of balls contained in the circular groove, a cage having radial openings for containing single balls and being rotatably mounted between said base and said brush, and means for rotating said brush.

2. A machine for cleaning golf and like balls comprising in combination, a cylindrical casing, a base to such cylindrical casing containing a circular groove eccentrically arranged relatively to the axis of said cylindrical casing, a brush rotatably mounted and adapted to contact with the upper surface of balls contained in the circular groove, a cage having radial openings for separating the balls, being suitably mounted between the base and the brush, a brake engaging the cage, and means for rotating said brush.

In witness whereof I have hereunto set my hand.

EDWARD GODFREY BREWER.
